(57) **CLAIM**

The ornamental design for a jewelry case, as shown and described.

DESCRIPTION

FIG. 1 is a front and left side perspective view of a jewelry case, showing my new design in a closed configuration;

FIG. 2 is a front elevational view thereof;

FIG. 3 is a rear elevational view thereof;

FIG. 4 is a left side elevational view thereof, the right side elevational view being a mirror image thereof;

FIG. 5 is a top plan view thereof;

FIG. 6 is a bottom plan view thereof;

FIG. 7 is a front and left side perspective view of the jewelry case in a partially open position, showing the mirror in a closed position;

FIG. 8 is a front and left side perspective view of the jewelry case in a partially open position, showing the mirror in a flipped up position; and,

FIG. 9 is a front and left side perspective view of the jewelry case in a fully open position, showing the mirror in a flipped up position.

The broken lines shown in the drawings illustrate portions of the jewelry case and form no part of the claimed design.
